LAMP CIRCUIT AND CONTROL

Clarence B. Fowler, Washington, D. C.

Application February 14, 1946, Serial No. 647,640

6 Claims. (Cl. 315—320)

(Granted under the act of March 3, 1883, as amended April 30, 1928; 370 O. G. 757)

1

This invention relates generally to a control circuit for lamps, and is particularly concerned with a control arrangement for a plurality of lamp filaments so arranged that, upon the burning out or failure of a first or primary filament, a second or reserve filament will be substituted.

It is the current practice on Naval and commercial vessels to require the use of navigation lights, and because of the importance which these lights may assume under certain conditions, as in preventing collisions and other sea disasters, efforts have been made to prevent the accidental extinguishment of such lights during use.

For such purpose, several expedients have been employed. In general, it has been the practice to provide a multifilament lamp in which two filaments are connected with three terminals which adapt the lamp for use in a three-wire socket. The lighting circuit in which such a lamp is installed is so arranged that one of these filaments becomes the "primary" filament, while the other filament becomes a "secondary" filament. As operated, the primary filament normally would be energized. Should this filament become broken or burned out, suitable switching means are employed to immediately throw the secondary filament into the circuit and energize it until such time as the lamp may be changed.

In the foregoing arrangement, the filaments are operated at full rated voltage, and when the primary filament is burned out an immediate substitution of the secondary filament may be made. Operation on the secondary filament is usually limited, however, for the reason that there is then no reserve filament available. Consequently, the lamp will as a rule be operated for only a short period of time after the secondary filament has been switched in. The potential life of the two filaments is therefore seldom realized.

Another defect of the present circuit control arrangements is that the secondary filament may become broken due to storms, collision, vibration or other cause, before it is called upon to function as a substitute for the primary filament. As ordinarily installed, a buzzer, annunciator or other signal means is provided to operate upon the burning out of the primary filament, but such signal is not arranged to operate in case the secondary filament burns out prior to the primary filament.

From data available in the electrical art, it is well known that the filament life of an incandescent lamp is appreciably prolonged when the filament is energized at reduced voltages. As an indication of the degree of prolongation, it may

be noted that in certain types of filaments, a decrease of the voltage to 85% of the rated lamp voltage will result in a life expectancy of four or five times that which may be expected when the filament is operated at normal rated voltage. The emitted illumination at this decreased voltage is in such case reduced to substantially 50% of its rated value.

In order to take advantage of the foregoing operational characteristics and prolong the life of the incandescent lamps utilized for important installations, such as navigation lights on ships, this invention proposes to utilize a lighting circuit in which both filaments will be simultaneously energized during normal operation. Both filaments are energized at a reduced voltage that will result in a combined illumination which is the equivalent of that secured from one of the filaments, when that filament is energized at full rated voltage. Thus, the two filaments will give the same illumination at reduced voltage as the one filament formerly used and energized at full rated voltage. The advantage, however, of the arrangement of my invention is that the life of the filaments will be materially prolonged.

My invention further proposes to provide switching and signal means which will become operative upon the burning out or damage of either one of the filaments, and automatically function to place the remaining filament in circuit and increase its applied voltage to full rated voltage. Thus the remaining filament will give full rated illumination. At the same time as this substitution occurs, a signal device is placed in the circuit to apprise interested personnel that one of the filaments has burned out and the other has been substituted. This signal device is arranged to operate irrespective of which filament is the first to burn out.

It is therefore a primary object of the present invention to provide an improved circuit and control for a plurality of lamp filaments, which will normally apply to the filaments a reduced voltage of such magnitude that the combined illumination of all the filaments will approximate the illumination emitted when the number of the filaments is reduced and normal full voltage applied to them.

It is also an object to provide improved control circuit and signal means for a plurality of lamp filaments, which will operate upon the burning out or failure of any one of the filaments.

A further object of the invention is to provide an improved method of operating a plurality of

2

lamp filaments, which will result in prolongation of the life of the filaments.

Still other objects and advantages of my invention will be apparent from the specification.

The features of novelty which I believe to be characteristic of my invention are set forth with particularity in the appended claims. My invention itself, however, both as to its fundamental principles and as to its particular embodiments, will best be understood by reference to the specification and accompanying drawing, in which the single figure diagrammatically illustrates a preferred embodiment of the invention.

As shown on the drawing, a lamp 10 is disclosed as being operatively connected into an electrical circuit generally indicated as 11 and having connections with a source of power at terminals 12 and 13. This power source may vary with different installations and may be alternating or direct current depending upon the particular installation.

The lamp 10, in this particular case, is shown as usually constructed for use in such places as where it may be desired to independently control the respective filaments. The two filaments are indicated at 14 and 15 respectively, and are connected to a common external terminal 16 at one end, whereas the opposite ends of the filaments are respectively connected to individual terminals 17 and 18 disposed exteriorly of the lamp envelope. Terminals 17 and 18 are commonly connected through a pair of suitable fuses 19 to one side of the circuit, while terminal 16 is connected with the other side of the circuit. This connection places the two filaments in parallel connected relation in the circuit.

In order to reduce the normal operating voltage applied to the filaments of lamp 10, a resistor 20 is inserted in the circuit between the power source terminal 13 and the fuses 19. This resistor is preferably made adjustable so that it may be varied to accommodate lamps of different operating characteristics. Although a resistor has been indicated for reducing the voltage, it will be appreciated that, for example, in an alternating current circuit, it may be found desirable to utilize an inductance rather than a resistor.

The side of the electrical circuit in which the resistor is inserted is connected through the operating coil of a double-pole current-responsive relay 21 which is operatively associated with movable contacts 22a and 22b. A control switch 23 is inserted in the circuit to control the general operation of the lamp, one side of this switch being connected through a main fuse 24 with the power source terminal 13 and the other side of the switch being connected with the circuit through the operating coil of relay 21.

Appropriate visual and audio signal devices may be provided as shown. For the visual signal, I provide an annunciator, as generally indicated by the numeral 25, having one terminal of its operating coil connected with the power side of switch 23 and its other terminal with the movable contact 22a of the relay 21. The contact 22a is arranged to engage, under appropriate current conditions, with a stationary contact 26a connected through conductor 27 with that side of the electrical circuit leading from the power source terminal 12.

The audio signal may comprise a buzzer, as generally indicated by the numeral 28, and is shown as having its terminals connected in parallel with the operating coil connections of the annunciator 25. A switch 29 may be placed in

the buzzer circuit so that it may be connected or disconnected relative to the circuit, as desired.

The movable contact 22b is connected with one side of resistor 20, and is operatively associated with stationary contact 26b in such manner that, upon closure, a short circuit is established around the resistor 20 through conductor 30.

Normal operation of my disclosed invention will be substantially as follows:

10 A power source being connected to terminals 12 and 13, and with switch 23 in closed position, the contacts of relay 21 will be actuated to open position and lamp 10 will have its two filaments energized through the resistor 20 at reduced voltage. It will be appreciated that with lamps of different characteristics, the voltage reducing element will necessarily have to be adjusted to values in which the combined illumination of the two filaments will be substantially the equivalent 15 of the illumination which would result by energizing one of the filaments at full rated voltage.

In the event that either of the filaments 14 or 15 should burn out or become open circuited, the current through the circuit will immediately 20 decrease by virtue of the increased resistance of the lamp 10. The relay 21 is so adjusted and designed that this decrease in circuit current will permit the contacts 22a and 22b to close with their associated contacts. The operation 25 of this relay places a short circuit around resistor 20 so as to apply substantially rated voltage to the remaining filament. Simultaneously, the circuit through the annunciator 25 is completed to cause its operation, and if switch 29 is 30 closed, the buzzer will also operate to give an audible signal.

It will be appreciated that the ohmic values of the resistor and the operating coil of relay 21 will be dictated by experience and depend upon the 35 rating characteristics of the lamp 10. In utilizing a lamp having two 50-watt filaments, I have found that satisfactory operation may be obtained by utilizing a resistor of 20.5 ohms and an operating coil on the relay 21 having a resistance of 2 ohms.

While the drawing discloses the utilization of a two-filament lamp, it will of course be understood that the invention is not to be thus limited, as separate lamps having individual filaments may be utilized, where these lamps are mounted sufficiently adjacent to emit their combined illumination as a unit. It will also be understood that a double filament lamp of the two-terminal type having the filaments connected in 55 parallel within the lamp envelope, may with equal facility be utilized.

The invention described herein may be manufactured and used by or for the Government of the United States of America for governmental purposes without the payment of any royalties thereon or therefor.

What is claimed is:

1. An apparatus comprising: a power source, a lighting circuit energized thereby including a plurality of lamp filaments in parallel and a variable resistor in series therewith, and automatic means responsive to change in current for shunting said resistor when the circuit of one of said filaments is opened.

70 2. A lamp circuit comprising filaments in multiple, a source of power for energizing the filaments, a resistance in series therewith, and a relay in series with the filaments operative to cause a predetermined illumination from all the filaments, and non-operative when the circuit of

one of the filaments is de-energized to maintain a shunt on the resistance to maintain an equivalent illumination from the remaining energized filament or filaments.

3. A lamp circuit comprising lamp filaments in multiple, a source of power for energizing said circuit, and a voltage control relay in said circuit, said relay being operative or non-operative to select one of a plurality of voltages depending upon the number of filaments energized.

4. A lighting circuit comprising a plurality of lamp filaments in multiple, variable impedance means connected in series to the multiple filaments, and control means for the impedance means operative responsive to opening of a filament to lower the impedance afforded by the impedance means.

5. The method of operating a plurality of lamp filaments which consists in simultaneously energizing the filaments at such voltage as to give a combined predetermined value of illumination, and thereafter upon failure of one of said elements increasing the voltage applied to the re-

maining filaments to give an equivalent illumination.

6. The method of operating two adjacent lamp filaments having corresponding ratings, which consists in simultaneously energizing the filaments at a voltage less than their normal rated value to give a predetermined combined illumination, and thereafter energizing one of the filaments at substantially rated voltage to give an equivalent illumination.
